UNITED STATES PATENT OFFICE.

WILLIAM HERRICK, OF CHICAGO, ILLINOIS, ASSIGNOR TO THE MORGAN & WRIGHT, OF SAME PLACE.

DESIGN FOR A GOLF-TEE.

SPECIFICATION forming part of Design No. 33,398, dated October 16, 1900.

Application filed December 14, 1899. Serial No. 740,360. Term of patent 14 years.

To all whom it may concern:

Be it known that I, WILLIAM HERRICK, residing at Chicago, in the county of Cook and State of Illinois, have invented and produced a new and original Design for Golf-Tees, of which the following is a specification, reference being had to the accompanying drawings, forming part thereof.

In said drawings, Figure 1 shows the golf-tee in side elevation. Fig. 2 is a plan of the same. Fig. 3 shows the tee in vertical section.

The tee shown is substantially frusto-conical in form, having a flattened crown 1 and a flaring or spread-out base 2. As illustrated

by Figs. 1 and 3, the outer surface 3 of the side walls is concave in vertical section and the inner surface 4 is convex. Thus formed the hollow tee is open top and bottom. The periphery 5 is blunt and on a curve reverse 20 to the curvature of the upper outer surface.

Having described my invention, what I claim as new, and desire to secure by Letters Patent, is—

The design for a golf-tee, substantially as 25 herein shown and described.

WILLIAM HERRICK.
